MANDREL FOR TUBE ROLLING MILLS

August P. Diescher, Pittsburgh, Pa., assignor to
Diescher Tube Mills, Inc., Pittsburgh, Pa., a
corporation of Delaware

Application March 3, 1933, Serial No. 659,531

10 Claims. (Cl. 78—103)

My invention relates to apparatus for treating tubular blanks, and particularly to mandrels for use in treating tubes of relatively large diameters by means of cross-rolling.

In reducing the wall thickness and increasing the length of tubes in a cross-rolling mill, it is advisable to employ a mandrel the outside diameter of which is smaller than the inside diameter of the finished tube. When the tubes are of relatively large internal diameter it will be appreciated that the weight of a solid mandrel of the necessary diameter may be such as to damage the relatively thin walls of a completed tube which encloses it when they are delivered from the cross-rolls.

A hollow mandrel of sufficient wall thickness to resist the forces exerted by the cross-rolls upon the tubular blank would be lighter than a solid mandrel, but its weight would still be excessive in connection with the handling of the completed large tube with the mandrel in the interior thereof.

In accordance with the present invention, I provide a relatively light tube, or cylindrical shell, the wall thickness of which is sufficient to withstand all of the stresses to which an elongator mandrel may normally be subjected in handling but is not sufficient to withstand the forces of cross-rolling that tend to crush the mandrel during the elongation of a tubular blank; and I provide in the interior of the hollow shell a reinforcing plug which may rotate with the hollow shell but is retained in its longitudinal position between the cross-rolls for receiving the forces of the latter as the tubular blank and the hollow shell pass therethrough.

The hollow cylindrical shell may therefore advance through the rolls and rotate with the tubular blank during its elongation, while the reinforcing plug in the interior thereof remains in its longitudinal position but may rotate with the shell. By means of this arrangement, I am enabled to provide a mandrel member to move with the tube of sufficiently light construction to be easily handled and to avoid damaging, by reason of its weight, the highly heated thin walls of tubes of large diameter as they emerge from the cross-rolls.

The details of my invention will be described in connection with the accompanying drawings, in which,

Figure 1 is a plan view of a portion of an elongator in operation upon a tubular blank having a mandrel constructed in accordance with my in-

vention, the blank and mandrel being in horizontal section and parts being broken away.

Fig. 2 is an enlarged longitudinal sectional view of a portion of the mandrel of Fig. 1.

Figs. 3 and 4 are views similar respectively to Figs. 1 and 2 of a modification.

Fig. 5 is a longitudinal sectional view of a portion of a mandrel of further modified construction.

Fig. 6 is a transverse sectional view taken on line VI—VI of Fig. 5.

Fig. 7 is a similar view on line VII—VII of Fig. 5.

Fig. 8 is a front end elevation of the mandrel of Fig. 5.

Referring particularly to Figs. 1 and 2, an elongator for suitably reducing the wall thickness and increasing the length of tubular blanks may comprise cross-rolls 1 and 2 and suitable guide discs therefor, illustration of the latter being omitted as not necessary to an understanding of the present invention. A tubular blank 3, which is illustrated in an intermediate stage of its elongation by the cross-rolls 1 and 2, is provided with a mandrel 4 therein.

The mandrel 4 comprises a relatively light cylindrical shell 5 that is provided with a conical head 6 which is screw-threaded into an end piece 7 and fastened therein by means of a suitable rivet 8. The end piece 7 is secured to the shell 5 by means of the rivet 8 and rivets 9.

A reinforcing plug 10 is located in the interior of the shell 5 for the purpose of resisting the crushing forces exerted by the cross-rolls upon the tubular blank 3 and shell 5 as they pass through the elongator. The plug 10 comprises a hollow cylindrical member 11 having tapered ends 35 and secured to the forward end of a tubular rod 12 which retains the assembly of the plug 10 in its illustrated longitudinal position.

The member 11 has a close or running fit with the interior of the shell 5 and may rotate with the latter. The rod 12 may be secured at its left-hand end, not shown, by any suitable means such, for example, as a thrust bearing which will restrain the rod 12 and the plug 10 from longitudinal movement to the right as viewed in Fig. 1, but which will permit the rotation of these parts with the shell 5.

The hollow member 11 is mounted upon a reduced portion of the rod 12 and is suitably keyed thereto by a key 13. The member 11 is secured upon the rod 12 by means of a bushing nut 14 screw-threaded on the forward end of the rod 12 and prevented from rotation by a suitable rivet 15.

The hollow member 11 is mounted upon a reduced portion of the rod 12 and is suitably keyed thereto by a key 13. The member 11 is secured upon the rod 12 by means of a bushing nut 14 screw-threaded on the forward end of the rod 12 and prevented from rotation by a suitable rivet 15.

The interior of the tubular rod 12 is provided

with a tube 16 that is spaced from the interior wall of the rod 12 and is secured to the forward end of the latter by means of interior screw-threaded bushings 17 and 18. The tube 16 serves 5 as an inlet for water for cooling the interior of the conical head 6 and of the hollow shell 5 of the mandrel 4 and the walls of the tapered member 11. The space around the tube 16 within the tubular rod 12 affords a passage having an 10 outlet through a radial tube 19 for a suitable lubricant for the interior surface of the shell 5 whereby the latter may move over the reinforcing plug 10 without undue friction there-between which might otherwise be caused by the 15 pressure exerted upon the plug 10 by the shell 5 because of the forces exerted by the cross-rolls 1 and 2.

In the operation of an elongator employing my 20 improved mandrel, a tubular blank is provided with a hollow shell 5 and a plug 10 is inserted 25 within the shell 5 against the mandrel head 6 at any suitable point in the travel of the blank and mandrel to the cross-rolls. It is preferable that the thrust block or other device for retaining the rod 12 and the connected plug 10 in their longitudinal positions be so arranged that it may 30 advance with the plug 10 and the shell 5 and tubular blank 3 until the plug 10 is in its working position between the cross-rolls as illustrated in Fig. 1.

When the tubular blank 3 enters the cross-rolls it is drawn longitudinally therethrough and rapidly rotated and the mandrel shell 5 which is closely engaged by the tubular blank 3 moves in the 35 same direction as the latter, but not necessarily at the same rate. The plug 10, however, remains in position between the cross-rolls in the zone in which forces are exerted by the cross-rolls in reducing the wall thickness of the blank 40 3 upon the mandrel 4. It will be appreciated that no wall-reducing forces are exerted upon the portion of the completed tube that has passed through the cross-rolls and is beyond the plug 10.

45 During the cross-rolling operation water is supplied through the tube 16 and it flows into the forward portion of the shell 5 beyond the plug. It is desirable that the water be supplied under such pressure and at such rate that its volume 50 beyond the plug will increase more rapidly than the space beyond the plug 10 in order that it will be under pressure to insure a satisfactory rapid return flow.

The cooling water returns along the shell 5 and 55 through a series of inclined openings 20 in the wall of the hollow member 11 to cool the latter. This cooling effect is increased by the rotation of the plug 10 since any water entering the openings 20 in the forward end of the plug will flow 60 around at least a portion of the interior of the hollow member 11 before it flows out through the openings 20 at the rear of the member 11. The returning cooling water continues to the trailing end of the mandrel shell, whereupon it may be 65 either cooled and recirculated or disposed of in any suitable manner.

In case such operation appears desirable, the 70 direction of flow of cooling water may be reversed, the water being supplied through the shell 5 surrounding the tube 12. This arrangement insures an adequate supply of cooling water to the plug 10 at all times since it flows through the openings 20 before passing to the forward end of the mandrel. Water will not return until it reaches a level 75

in the forward end of the mandrel that permits it to flow into the forward end of the tube 16.

The cross-rolling operation continues until the entire blank 3 has passed through the cross-rolls to the delivery side of the elongator.

If the elongating apparatus is of the type in which the mandrel is returned to its starting point by passing around the elongator in the manner described, for example, in my copending application Serial No. 602,145, filed March 31, 1932, it will be necessary that the plug 10 be withdrawn after the elongation of each tube and for such distance from the cross-rolls on the entry side thereof as will permit a fresh mandrel shell to be placed into position to enter the cross-rolls. The plug may then be advanced into the forward end of the fresh mandrel shell at any suitable time before the tubular blank enters the cross-rolls. All of these parts are then advanced into the cross-rolls.

In the event that the elongating apparatus is of the type wherein the mandrel is stripped from the completed tube by drawing it back through the cross-rolls after each elongation, the plug 10 must be withdrawn along with the mandrel 25 shell for such distance as is sufficient to permit the next tubular blank or billet to be disposed in the elongator inlet between the mandrel head or point and the elongator. In withdrawing the mandrel shell in this manner the plug 10 will 30 necessarily be carried with it after the mandrel head has engaged the forward end of the rod 12 to which the plug 10 is secured.

Referring to the modification shown in Figs. 3 and 4, the general arrangement is similar to that 35 of the mandrel of Figs. 1 and 2 but differs therefrom in certain details of construction. The hollow tapered member 11 is provided with an axial stem 22 into the trailing end of which is secured a tubular rod 23. Within the rod 23 is a pipe 24, 40 the forward end of which is connected to the stem 22 by means of a washer 25 and an internal bushing 26.

A tapered nozzle 27 has a screw-threaded connection to the interior of the hollow stem 22 and 45 is in alignment with the pipe 24. Between the bushing 26 and the rearward end of the nozzle 27 is a series of radial openings 28 that extend through the stem 22 and communicate with the hollow interior of the tapered member 11. The nozzle is also provided with radial openings 29 50 adjacent its screw-threaded connection to the stem 22.

In the operation of this form of my invention, water is supplied through the pipe 24 and it is 55 forced forwardly through the nozzle 27 toward the forward end of the mandrel. In addition a certain amount of water flows radially through the radial openings 28 for the purpose of cooling the interior of the member 11. Water also flows 60 radially through the openings 29, this portion of the water flowing at the forward end of the stem 22 into the shell adjacent the forward end of the hollow member 11.

It is possible that during the operation of the 65 cross-rolls the mandrel shell 5 may advance with the tubular blank 3 at such rate as compared to the rate of water supply that the water does not fill the rapidly increasing space in front of the member 11. In such case water from the space 70 in front of the member 11 will not flow back through the front and rear openings 20 of the member 11. It is important therefore in such case that means such as the radial openings 28 be provided in order to insure that a certain portion of 75

the cooling water flows into the interior of the member 11. The nozzle 27 provides sufficient back pressure to the flow of water through the pipe 24 that water will flow radially through the 5 openings 28 and also through the openings 29 for the purposes described above.

In case the forward end of the mandrel is not filled by the cooling water, the nozzle 27 will operate to so increase the velocity of the water that 10 it will be thrown a considerably greater distance toward the forward end of the mandrel than would be the case if the water flowed through a pipe of uniform bore.

Reference may now be had to Figs. 5, 6, 7 and 8 15 in which is illustrated a further modification. As in the form of my invention shown in Figs. 3 and 4, the member 11 is provided with a central stem 30 to which is connected a tubular rod 23. A pipe 24 is connected to the stem 30 in the manner described in connection with the apparatus of Figs. 3 20 and 4.

The forward end of the stem 30 is provided with a bushing 31 through which projects a pipe 32 that is rigidly connected to a bushing 33 in the 25 head of the mandrel. The pipe 32, which is provided with a series of radial openings 34 adjacent the head of the mandrel, has a loose telescoping fit with the pipe 24, these parts overlapping to such extent as to permit the movement of the 30 mandrel shell during the operation of cross-rolling a tube without the tube 32 being completely withdrawn from the pipe 24.

The mandrel head comprises a tubular bushing 36 that is secured to the forward end of the shell 35 5 by means of rivets 37 and an approximately conical nose portion 38 is screw-threaded to the bushing 33, the latter having a similar connection to the tubular bushing 36. As shown in Fig. 8 the nose portion 38 is provided with two recesses 39 40 whereby the nose 38 may be removed from or replaced upon the bushing 33. A screw 40 locks the nose 38 in its illustrated position.

In the operation of the latter form of my invention, water is supplied through the pipe 24 45 in the direction of the arrow in Fig. 5, water flowing into the pipe 32 and being discharged therefrom through the openings 34 at the forward end of the mandrel. Water also traverses the annular space between the pipe 24 and the pipe 32 and enters the annular space within the stem 30. The latter is provided with radial openings 41 through which water is forced into the interior of the hollow tapered member 11.

Water also flows through the relatively small 55 annular opening in the bushing 31 surrounding the pipe 32 and is discharged into the shell 5 adjacent the forward end of the member 11. The return flow of the cooling water is through the inclined openings 20 as in the other forms of 60 my invention. If the rate of increase in the volume of the space within the mandrel shell in front of the member 11 is faster than the rate at which water is supplied thereto, there may be little or no return flow through the openings 65 20 from such space. In such case, however, the arrangement whereby the water is transmitted to three portions of the mandrel insures that all of the essential parts of the latter will be cooled regardless of the relation of the rate of increase in space to that of the supply of water. The openings 34 insure that the forward end of the mandrel will be cooled, and the openings 41 insure that water will be supplied to the interior of the member 11. The water flowing through the annular opening in the bushing 31 insures

that some water will be directed to a portion of the shell adjacent the member 11.

Mandrels constructed in various forms in accordance with my invention permit the cross-rolling of a tube of relatively large diameter upon a mandrel of such weight that it is easily handled and that the highly heated thin walls of the tube will not be damaged when the tube and the mandrel shell therein emerge from the cross-rolls. At the same time the strength of the mandrel shell reinforced by the plug contained therein is sufficient to resist the crushing forces of the cross-rolls and to thereby insure that the elongation of the tubular blank will occur with the same efficiency and satisfactory results that would be secured if solid mandrels were employed.

The foregoing and other advantages will be apparent to those skilled in the art of construction and operation of apparatus for the treating 20 of tubular blanks.

I claim:

1. A mandrel adapted for use in a tube rolling mill, comprising a rod held against longitudinal movement, a plug having a cylindrical outer face attached to said rod and adapted to be held 25 thereby in the working pass of a mill, and a long cylindrical blank-supporting shell slidably mounted for longitudinal movement upon said plug which is formed to reinforce said shell throughout the latter's annular extent as the shell progresses forwardly over the plug.

2. A mandrel adapted for use in a tube rolling mill, comprising a rod anchored at its outer end for rotation on its axis and against longitudinal movement, a plug having a cylindrical outer face 35 attached to said rod and adapted to be held thereby in the working pass of a mill, and a long cylindrical blank-supporting shell slidably mounted for longitudinal movement upon said plug which is formed to reinforce said shell 40 throughout the latter's annular extent as the shell progresses forwardly over the plug.

3. A mandrel adapted for use in a tube rolling mill, comprising a rod held against longitudinal movement, a plug having a cylindrical outer face 45 attached to said rod and adapted to be held thereby in the working pass of a mill, and a long cylindrical blank-supporting shell slidably mounted for longitudinal movement upon said plug and provided at its forward end with a 50 tapered head for entering the shell into a tubular blank, said plug being formed to reinforce said shell throughout the latter's annular extent as the shell progresses forwardly over the plug.

4. A mandrel adapted for use in a tube rolling 55 mill, comprising a rod held against longitudinal movement, a plug having a cylindrical outer face attached to said rod and adapted to be held thereby in the working pass of a mill, and a long cylindrical blank-supporting shell slidably 60 mounted for longitudinal movement upon said plug and having its forward end closed by a tapered head for entering the shell into a tubular blank, said plug being formed to reinforce said shell throughout the latter's annular extent as 65 the shell moves forwardly over the plug.

5. A mandrel adapted for use in a tube rolling mill, comprising a tubular rod anchored at its outer end against longitudinal movement, a plug having a cylindrical outer face attached to said 70 rod and adapted to be held thereby in the working pass of a mill, a long cylindrical blank-supporting shell slidably mounted for longitudinal movement upon said plug and having its forward end closed, said plug being formed to reinforce 75

said shell as the latter moves forwardly over the plug and being provided with openings for the flow of cooling fluid through it and through said tubular rod.

5 6. A mandrel adapted for use in a tube rolling mill, comprising a tubular rod anchored at its outer end for rotation on its axis and against longitudinal movement, a plug having a cylindrical outer face attached to said rod and adapted to be held thereby in the working pass of a mill, 10 and a long cylindrical blank-supporting shell slidably mounted for longitudinal movement upon said plug and provided with an end-closing head which is tapered for entering the shell into 15 a tubular blank, said plug being formed to reinforce said shell as the latter moves forwardly over the plug and being provided with openings for the flow of a cooling fluid through it and through said tubular rod and to the closed end 20 of said shell.

7. A mandrel for use in a tube rolling mill, comprising a long cylindrical shell adapted to advance longitudinally within a tubular blank during passage of the blank through the mill, a reinforcing plug within said shell having a cylindrical outer face, and a rod extending within the shell and held at its outer end against longitudinal movement, said plug being attached to 25 said rod and held thereby against longitudinal movement positioned in the working pass of the mill while the shell advances longitudinally.

8. A mandrel for use in a tube cross-rolling mill, comprising a long cylindrical shell adapted to rotate and advance longitudinally within a 30 tubular blank during passage of the blank through the mill, a reinforcing plug within said

shell having a cylindrical outer face, and a rod extending within the shell and held at its outer end against longitudinal movement, said plug being attached to said rod and held thereby against longitudinal movement positioned in the working pass of the mill while the shell advances longitudinally, said plug being free to rotate with 5 said shell.

9. A mandrel for use in a tube cross-rolling mill, comprising a long cylindrical shell adapted to 10 rotate and advance longitudinally within a tubular blank during passage of the blank through the mill, a reinforcing plug within said shell having a cylindrical outer face, and a rod extending within the shell and held at its outer end against longitudinal movement but free to 15 rotate, said plug being attached to said rod and held thereby against longitudinal movement positioned in the working pass of the mill while the shell advances longitudinally. 20

10. A mandrel for use in a tube rolling mill, comprising a long cylindrical shell adapted to advance longitudinally within a tubular blank during passage of the blank through the mill, a reinforcing plug within said shell having a cylindrical outer face, and a rod extending within the shell and held at its outer end against longitudinal movement, said plug being attached to 25 said rod and held thereby against longitudinal movement positioned in the working pass of the mill while the shell advances longitudinally, and said rod and plug being provided with a passage-way for supplying lubricant to the exterior of the plug. 30

AUGUST P. DIESCHER. 35
